CLAIM

The ornamental design for a remote control, as shown and described.

DESCRIPTION

FIG. 1 shows a top perspective view of a remote control according to a first embodiment.

FIG. 2 shows a bottom perspective view thereof.

FIG. 3 shows a top plan view thereof.

FIG. 4 shows a front view thereof.

FIG. 5 shows a rear view thereof.

FIG. 6 shows a left side view thereof.

FIG. 7 shows a right side view thereof.

FIG. 8 shows a bottom view thereof.

FIG. 9 shows a top perspective view of the remote control according to a second embodiment.

FIG. 10 shows a top plan view of the remote control according to the second embodiment, wherein the bottom perspective, front, rear, left side, right side, and bottom views of the second embodiment are identical to the bottom perspective, front, rear, left side, right side, and bottom views, respectively, of the first embodiment.

FIG. 11 shows a top perspective view of the remote control according to a third embodiment; and,

FIG. 12 shows a top plan view of the remote control according to the third embodiment, wherein the bottom perspective, front, rear, left side, right side, and bottom views of the third embodiment are identical to the bottom perspective, front, rear, left side, right side, and bottom views, respectively, of the first embodiment.

The broken lines showing portions of the remote control are included to show unclaimed subject matter only and forms no part of the claimed design.

1 Claim, 10 Drawing Sheets
